UNITED STATES PATENT OFFICE.

JACQUES REIMANN, OF ERDINGTON, BIRMINGHAM, ENGLAND.

TUBE-ROLLING MILL.

1,399,401.

Specification of Letters Patent.

Patented Dec. 6, 1921.

Application filed August 21, 1919. Serial No. 318,964.

To all whom it may concern:

Be it known that I, JACQUES REIMANN, a subject of the King of England, residing at Erdington, Birmingham, England, have 5 invented certain new and useful Improvements in Tube-Rolling Mills, of which the following is a specification.

This invention is for improvements in or relating to machines for manufacturing 10 weldless tubes and has particular reference to the type of machine in which the tubes are carried upon a mandrel which is progressively advanced and partially rotated between grooved rollers. Where a sleeve 15 carried by the mandrel-holder extends on to the mandrel to bear against the end of the bloom and receive the latter's thrust during the rolling process, a screw-threaded connection has been provided between the 20 sleeve and the mandrel-carrier, so that toward the end of the rolling process the sleeve can be retracted sufficiently from the bloom to enable the latter to be finished to its end, thus avoiding waste and facilitating 25 its subsequent removal from the machine in the direction of rolling. Usually the means provided for this purpose comprised 30 spokes on the sleeve to rotate it and thus move it endwise, but such means could not 35 conveniently be employed while the machine was working in the usual manner at its normal speed.

It is the principal object of the present 40 invention to provide means for operating the sleeve positively in either direction of endwise movement without interfering with the normal action of the machine. A further object is to provide a simple means of attaching the mandrels to the mandrel carrier and locking them by means of the aforesaid sleeve.

In the accompanying drawings, which 45 illustrate the manner of carrying out this invention,

Figure 1 is a sectional plan of part of a rolling mill showing the mandrel housing, the sleeve, mandrel holder, and mandrel, with a partly-rolled tube thereon between the rollers, the latter for clearness being 50 shown in sectional side elevation.

Fig. 2 is a cross-sectional view on the line 2-2 of Fig. 1 as seen in the direction of the arrow X.

Fig. 3 shows the end portion of a tube passing through the rolls with the sleeve 55 retracted from the tube sufficiently for that purpose, and

Fig. 4 shows a modification in the means for connecting the sleeve with the rotatable member which operates it. 60

Fig. 5 is a view of the mandrel and sleeve disconnected at the joint.

Like letters indicate like parts throughout the drawings.

The frame A of the rolling-mill carries in 65 usual manner the traveling housing B which supports the mandrel holder C. The latter has formed upon it the feeding-spiral C¹ of known form and is also provided with a raised screw-thread C² which engages a corresponding internal screw-thread formed in a sleeve D. The latter extends beyond the end of the mandrel holder C on to the mandrel E which is connected to the mandrel holder by a joint E¹ to be hereunder 70 described. Sufficient length of screw-threaded connection of the mandrel holder C and sleeve D is provided to enable the latter to be completely retracted upon the mandrel holder when it is desired to uncover the joint E¹. 80

The sleeve D is free to rotate and to move endwise in the housing B, and carries upon it a spur-wheel F, to receive which a recess B¹, in which it can rotate but not move endwise, is provided in the housing. The spur wheel F is operatively connected to the sleeve D by a featherway D² which engages a featherway D³ in the sleeve D, of a length 85 to provide for the latter's full endwise travel. A pinion F¹ meshes with the spur-wheel F and is fast upon a shaft F² rotatably mounted in the housing B and operatively connected to an electro-motor (not shown in the drawing) which is preferably 90 mounted on some part of the traveling housing B. 95

The connection above referred to for the mandrel holder C and mandrel E is made by reducing the end of the latter and forming in the so reduced part a T-shaped end E¹ which can engage by a lateral movement a correspondingly-shaped slot C³ in the side of the mandrel-holder C. When the sleeve D extends over this joint the mandrel E 100 cannot be accidentally disengaged from the 105

mandrel holder. By employing this form of joint, mandrels can be rapidly changed, and are always securely locked when the sleeve D is in its normal position.

- 5 In use the sleeve D occupies the position shown in Fig. 1 thus securing the joint E¹ and receiving on its end the thrust of the bloom or tube H during the rolling process. Sufficient frictional grip exists in the 10 threaded connection of the mandrel holder C and sleeve D to insure the latter rotating freely in the housing B during the known action of the feed spiral C¹, without rotational displacement upon the mandrel holder C, and during this action the spur-wheel F is carried around with it, thus rotating idly and in harmony with it the pinion F¹, shaft F² and the electro-motor to which it is connected.
- 15 20 As the unfinished end of the tube H approaches the rolls J, J¹, the electro-motor is so operated as to rotate the pinion F¹ to thereby cause the spur-wheel F and sleeve D to be rotated relatively to the mandrel holder C so that the threaded connection between the last two causes the sleeve D to be retracted from the end of the tube H. In this way the tube can be completely rolled to its end thus utilizing a part thereof 25 usually wasted. It will be apparent that to move the sleeve in the opposite direction it is only necessary to reverse the direction of rotation of the electro-motor.

It will be seen that by suitably arranging the gearing the sleeve D can be retracted during the action of the spiral feed device by simply holding the shaft F² against rotation, and can also be advanced by rotating the shaft F² at a higher speed than it 30 would attain when idling.

In the modified arrangement shown in Fig. 4 the featherway D³ is given a spiral path, and this arrangement in conjunction with an appropriate pitch of the thread C² on the mandrel holder allows the sleeve to move rearwardly as the thrust of the tube upon it increases and tends to become excessive. For instance, assuming the gear F to be fixed on the outward stroke, the 45 sleeve D would travel backward in a spiral path of great pitch. At the same time the screwed mandrel holder would move backward but would not revolve.

The sleeve, however, would move back in 50 a straight path relative to the mandrel holder a distance equal to that spiral movement of the sleeve transmitted through the threads C², there being no tendency to jam.

It will be seen from this that the sleeve 55 would travel a greater distance horizontally than the mandrel holder and would leave a gap between the sleeve head and the hollow bloom, thereby enabling the operator to introduce the extracting door or gate and 60 facilitating the withdrawal of the mandrel.

Further, on the return stroke the gear F would be free to revolve, when there would be no spiral motion imparted to the sleeve, but nevertheless, the mandrel holder would revolve through an angle of about 90° caused by the spiral C¹ working in the ratchet-box at the rear end of the machine. (This latter not being shown on the drawing.) It will be seen from this that when the operation of rolling is nearing the end, the gear 75 would be locked by some suitable means which would allow it to move in one direction only and this would cause the sleeve to retreat from the hollow bloom automatically and positively, by successive stages, 80 and leaving the end clear for finishing.

This backward motion of the sleeve would also, incidentally, assist the motor driving the gear F to pick up speed.

It is to be understood that this invention is 85 not limited to the employment of spur wheels and pinions to operate the sleeve, for which purpose any appropriate type of gearing may be employed. Furthermore, for the junction of the mandrel and mandrel 90 carrier, any form of head other than a T-shaped one may be employed provided it will transmit both torque and end-thrust.

It will be understood that to suit various diameters of mandrels correspondingly 95 sized sleeves are employed.

What I claim as my invention and desire to secure by Letters Patent is:—

1. In a tube rolling mill, the combination of a mandrel holder, which is progressively advanced and partially rotated, a tube carrying mandrel connected thereto, a sleeve screw-threaded upon said mandrel-holder, and extending over the junction of the mandrel holder and mandrel, a shaft geared to 100 said sleeve and normally rotating in harmony with it, and means, for rotating said shaft variably with reference to its normal movement, substantially as set forth.

2. In a feed mechanism for a tube rolling 110 mill of the type referred to a sleeve adapted to engage an end of a bloom, means for positively retracting the sleeve from the bloom, or returning it thereto at will, comprising a shaft parallel with the sleeve axis 115 geared to the sleeve thereby to be rotated normally in harmony with it, and driving means whereby the said shaft may be rotated at a speed above or below its normal speed, or may be stopped and have its direction 120 of motion reversed, substantially as set forth.

3. A feed mechanism for a tube rolling mill as claimed in claim 1, in which the sleeve extends through a rotatable member 125 which travels with the mandrel holder, a connection being provided between the sleeve and the rotatable member which permits endwise, and also rotary relative motion, substantially as set forth.

4. In a feed mechanism for a tube rolling mill as claimed in claim 1, the employment of a joint to connect the mandrel holder and mandrel which can be disconnected by a
5 lateral movement and is locked by means of the sleeve aforesaid, substantially as set forth.

In testimony whereof I have signed my name to this specification in the presence of two subscribing witnesses.

JACQUES REIMANN.
